Application March 31, 1934, Serial No. 718,348

20 Claims. (Cl. 20—69)

My invention relates to weather stripping and particularly to the metallic type of weather stripping to be used with casement windows, doors and double hung windows.

5 Among the objects of my invention are these: A single standard form of weather stripping adaptable to both casement and double hung windows; a weather stripping which can be applied to the edge face of a casement or door and operate in conjunction with a groove in the frame facing the inner face of the casement or door where the groove can be relatively wide without requiring a substantial space for the weather stripping beyond the edge of the casement or door; 10 a tight fitting weather stripping applicable to the edge of a door or casement remote from the hinge edge but still permitting clearance in swinging necessitated by the hinge pintle being on the side of the casement or door opposite the side on which the weather stripping seals; a single standard form of weather stripping which is adaptable to the different kinds of relative movement at the hinge edge and the latch edge of a casement or door, that at the latch edge being 15 transverse to the door and that at the hinge edge being parallel with the door; provision for sealing the door or window at the corners where the ends of the lengths of weather stripping come together; and an improved drain for use in connection with weather stripping especially on in- 20 swinging casements to drain water back to the sill.

The foregoing, together with further objects, features and advantages of my invention are set forth in the following description of specific embodiments thereof which are illustrated in the accompanying drawings wherein:

Fig. 1 is a perspective view of a section of my weather stripping;

Fig. 2 is a horizontal section through an in-swinging wood casement window and its frame to which my weather stripping has been applied, and may be considered as taken on the line 2—2 of Fig. 4;

Fig. 3 is a fragmentary view similar to Fig. 2 but showing only the latch edge of the casement sash and showing it in position just before the latch cams it tightly shut;

Fig. 4 is a vertical transverse section through the casement sash and its frame which may be considered as taken on the line 4—4 of Fig. 2;

Fig. 5 is a fragmentary detail perspective view of the lower, inside face, latch edge corner of the casement sash looking in an upward and forward direction;

Fig. 6 is a fragmentary detail perspective view

of the section at the right-hand side of Fig. 2 but with the casement swung open through 180°;

Fig. 7 is a fragmentary detail perspective view of the inside face of the upper latch side corner of the casement sash showing the miter joint of the weather stripping at the corner;

Fig. 8 is a horizontal detail section through the meeting (or lock edge) rails of a pair of casement sash;

Fig. 9 is a vertical transverse section through 10 a double hung window and its frame to which has also been applied the weather strip of Fig. 1; and

Fig. 10 is a horizontal section through the jamb 15 of the window of Fig. 8 and may be considered as taken on the line 10—10 of Fig. 9.

The weather stripping of my invention, best illustrated in Fig. 1, is preferably formed from a continuous flat strip of sheet high tension commercial spring bronze of .005 inch thickness, which is rolled to the form shown. The weather stripping 16 in cross section comprises two U-shaped portions 11 and 12 disposed at right angles to each other and arranged somewhat in the form of a figure 5. The width of each U-shaped portion is substantially equal to its height. Attention is directed to the relative positions of the U-shaped portions 11 and 12. The U-shaped portion 12 is spaced from the portion 11 and so disposed that its bight is opposite and faces one leg 11a of the U-shaped portion 11. An extension 13 of the leg 12a of the U-shaped portion 12 extends between and interconnects the two U-shaped portions 11 and 12. The far leg 11b of the U-shaped portion 11—far in relation to the interconnecting web 13—carries at its extremity an outwardly directed flange 11c. Similarly the far leg 12b of the U-shaped portion 12 carries an outwardly directed flange 12c. The connecting web 13 is a co-planar extension of the near leg 12a of the U-shaped portion 12. If an imaginary line such as 14 of Fig. 1 be drawn to define what would otherwise be the edge of the near leg 12a if it were of the same length as the far leg 12b, it will be seen that the space represented by the connecting web 13, by which the U-shaped portion 12 is spaced from the U-shaped portion 11, is substantially the same as the length or breadth of either of the U-shaped portions. Thus, ignoring the flanges 11c and 12c, the area of the cross-section of my weather stripping can be considered as divided into equal thirds, each third being substantially square, one-third being occupied by the U-shaped portion 11, the second by the intervening space between the U-shaped portions and including the web 3 and

the third the U-shaped portion 12. I am mentioning this better to describe the form and proportion of my weather stripping as I prefer to make it, and is not to be construed as an essential limitation.

It is a feature of my weather stripping that each of the leg portions of the U's is reinforced or stiffened adjacent its edge, thereby giving not only the weather stripping as a whole but each 10 component part thereof a stiffening. In general, the U-shaped portions 11 and 12 reinforce each other as to the component parts. The flange 11a is stiffened at one edge by the interconnecting web 13 and at the other edge by the arcuate 15 portion of the U. The leg 11b is reinforced at one edge by the arcuate portion and at its other edge by the flange 11c. The leg 12b is stiffened at one edge by the flange 12c and at its other edge by the arcuate curve of the U-shaped portion 12. The leg 12a is stiffened at one edge by the curve of the U-shaped portion 12 and at its other edge, by extension through the web 13, by the leg 11a. In this manner I avoid the objection 20 so often encountered in other types of weather stripping of the thin sheet metal portions which are relied upon to effect the seal becoming wavy due to lack of stiffening, and by the waviness, permitting the leakage of air.

I shall first describe the application of my 30 weather stripping to the instance of an inswinging wood casement window as illustrated in Figs. 2 to 7 inclusive. The application of my weather stripping to a door is so similar to the application to a casement window, that I believe it is unnecessary to illustrate the application to the door specifically. For the purpose of the description and claims of this application, the casement sash may be considered a door.

The casement sash comprises the usual top and 40 bottom rails 15 and 16 and hinge and latch stiles 17 and 18. The frame comprises the head 19, stool 20, sill 21 and jambs 22. The head, stool and jambs are shouldered as at 23 to provide an abutment for the outside face of the sash. The 45 sash is mounted on hinges whose pintles 24 are at the inside face of the sash. The opposite stile 18 carries a latch 24—or preferably two latches, one near the top and the other near the bottom. The latch here shown is of the rotating type 50 which engages the cam surface 25' of a cooperating latch piece 25 on the frame, in such manner that the sash is cammed tightly shut.

A groove 26 is run along the top edge and the 55 two lateral edges of the sash spaced inwardly somewhat from the outer face of the sash. Referring to the left-hand portion of Fig. 2, which shows the groove 26 in the lateral latch edge of the sash, a length of my weather stripping, equal to the height of the sash, is mounted on the edge 60 of the sash. This is done by inserting the U-shaped portion 11 into the groove 26 and securing it there by nails 27 at intervals through the bottom of the U-shaped portion. In planning the edge of the sash, a shallow depression 28 is formed for the reception of the flange 11c of the weather stripping, and if desired and preferably, the cut is extended in width to include that portion of the edge of the sash between the groove 26 and its outer face, whereby the web 13 and 65 the flange 11c may lie in the same plane rather than being slightly offset. The distance by which the groove 26 is set back from the outside face of the sash is such as to leave an intervening portion of the edge of the sash equal in transverse 70 width to the distance between the U-shaped por-

tions 11 and 12 of the weather stripping, which is the width of the interconnecting web 13. As a result, the flange 12c normally rests against the outside face of the sash.

The groove 26 is of slightly less width than the 5 normal width of the U-shaped portion 11 so as to insure a tight fit of the U-shaped portion 11 in the groove 26 when the U-shaped portion 11 is secured in place by the nails 27. A groove 29 in form similar to the groove 26 is provided in 10 the shoulder 23 of the jamb 22, one wall of the groove being a continuation of the sash opening 30. The groove 29 is also of slightly less width than the portion 12. The shoulder 23 preferably has a shallow depressed seat 23' formed 15 therein for the reception of the flange 12c, thereby enabling the remainder of the shoulder 23 to contact and form a tight abutment for the outside face of the sash.

Referring now to Fig. 3, which shows the position of the parts before the final closing movement of the door afforded by the camming action of the latch, the surface of the sash opening is offset slightly from the adjacent lateral wall of the groove 29. There is a sufficient clearance between this surface and the edge of the sash to permit the outswinging of the sash, the hinge pintle 24 being at the outer face of the sash. For the same reason the lock edge of the sash is slightly beveled. The clearance and bevel 30 between the surface 30 and the edge of the sash, together with the resiliency of the U-shaped portion 12, permit the easy opening and closing of the sash between the open position and that of Fig. 3. As shown in Fig. 3, as the sash is cammed 35 shut by the latch, the leg 12a of the weather stripping is normally spaced a slight distance from the contact with the adjacent wall of the groove 29. On the other hand, the leg 12b normally tends to overlap the opposite wall of the 40 groove 29. As the latch cams the door shut, the corner formed by the wall of the groove 29 and the shallow seat 29' contacts the curve of the U-shaped portion 12 near the leg 12b, and cams the entire portion 12 toward the left, whereby 45 it may enter the groove. In the final position, as shown in Fig. 2, this camming or shifting of the U-shaped portion 12 to the left has resulted in a pressure contact of the leg 12a against the adjacent wall of the groove 29, while there is a 50 second pressure contact of the leg 12b against the opposite wall of the groove 29 adjacent the recessed shoulder seat 23'. The two legs 12a and 12b are compressed together against their 55 normal resiliency, whereby they maintain this double seal against the groove 29, and this double seal is maintained notwithstanding that the outer face of the sash may be warped somewhat out of a vertical plane.

The arrangement and operation of the weather 60 stripping is substantially the same for the top edge of the sash. Referring to the top of Fig. 4, the clearance between the sash and frame is not made necessary by the slight throw occasioned by the position of the hinge pintle, but a similar clearance is nevertheless of advantage to prevent binding or sticking of the sash in the frame, especially such as might develop from a slight sag of the hinges.

Substantially the same application and arrangement of my weather stripping is also used at the bottom, as shown in Fig. 4, except that the shoulder 33 of the stool 20 is set inwardly 65 relative to the outer face of the sash, and the groove 26 is correspondingly spaced farther in- 70 75

wardly. A channel 34 is formed in the upper face of the sill beneath the weather stripping and forwardly of the shoulder 33, and this channel drains outwardly on to the sill 21 through ducts 35 spaced at intervals along the channel 34. The inner wall of the channel 34 is obliquely disposed at substantially the same angle as the oblique ducts 35 so that if they should become clogged, they may readily be cleaned by a straight wire or equivalent instrument from the inside of the house. The sloping wall of the channel 34 also facilitates brushing dirt out of the channel.

The application of my weather stripping to the instance of the hinge edge of the sash, as shown at the right hand of Fig. 2, is structurally similar to that employed at the latch edge, but the operation is different. At the latch edge, the sash moves relatively to the frame in a direction toward the shoulder 23. At the hinge edge, on the other hand, the closing movement of the sash relative to the frame is not toward the shoulder 23 but substantially parallel with it and toward the surface 30 of the sash opening. In providing for this different character of relative movement of the sash and frame, I use the same groove 26 in the sash and groove 29 in the jamb, and I position the weather stripping the same way, but instead of having the weather stripping carried by the sash it is carried by the frame. Thus the nails 27 are driven through the portion 12 of the weather stripping and into the jamb adjacent the sash opening 30. In this case the U-shaped portion 12 of the weather stripping permanently occupies the groove 29, and because it is normally wider than the groove 29, resiliently seals against the walls of the grooves at two opposite regions. The U-shaped portion 11 removably enters the groove 26. The fully opened position is shown in Fig. 6. Because the groove 26 is of slightly less width than the normal width of the U-shaped portion 11, when the door is swung shut, the legs of the U-shaped portion 12 are pinched between the walls of the groove 26, affording two opposed regions of seal.

I shall next explain how I arrange my weather stripping at the several corners of the sash, so as to prevent leakage of air at the corners. At the corner where the top weather stripping and the latch edge weather stripping meet, as shown in Fig. 7, I employ a simple miter joint which is not soldered or brazed. Where the bottom weather stripping and the sash side weather stripping form a corner, as illustrated in Fig. 5, they are not aligned.

The bottom edge of the sash edge weather stripping extends to the top edge of the face of the stool above the shoulder 33. The bottom weather stripping simply extends to and terminates in the plane of the latch edge of the sash. However, the space designated by 36 in Fig. 5 is filled by the portion of the stool 37 of Fig. 4 which also seals the bottom end of the edge weather stripping. Fig. 6 shows the disposition of the weather stripping at the bottom hinge corner of the sash, where the end of the frame-carried weather stripping abuts the portion 37 of the stool and the hinge end of the bottom weather stripping comes against the surface 30 of the sash opening. At the corner formed by the frame carried weather stripping on the hinge jamb and the weather stripping at the top of the sash, the aligned ends of the weather stripping may be mitered somewhat as in Fig. 7 with this difference, that one is carried by the frame and the other by the sash

whereby they come into miter corner relation only when the sash is closed.

Where, instead of a single casement sash in the sash opening of a frame, there is a pair of casement sash, weather stripping must be provided at the meeting vertical rails of the two sash. The application of my weather strip to this instance is shown in Fig. 8.

I shall now describe the application of my weather stripping to the instance of a double hung window. This is shown in Figs. 9 and 10. The frame, which may be of standard construction, comprises side jambs 40, head jamb 41, stool 42, sill 43, inside stop 44, blind stop 45 and parting stop 46. In the particular frame here illustrated I have incorporated the interlocking tongue and groove 47 between the jamb and the blind stop, which is the subject-matter of my Patent No. 1,930,801 of October 17, 1933, on Window frames. So that the groove in the blind stop which accommodates my weather stripping will not interfere with ample support for the base of the tongue of the interlock 47 the latter is shifted inwardly from the face of the jamb.

The lower sash 48 is mounted in the frame between the inside stop 44 and the parting stop 46, while the outer or upper sash is mounted in the frame between the parting stop 46 and the blind stop 45. The sash are free to reciprocate vertically in the usual manner, being balanced by the sash weights 50 and sash cords 51 which pass over sash pulleys 52 journalled in pulley frames 53 set into the face of the side jambs.

It is a feature of my invention that my weather stripping can be—and in fact preferably is, as is here shown—applied to double hung sash so that the weather stripping stands in the same position relative to the sash and frame as in the application to doors or casement windows. Thus, as shown in Fig. 10, the lateral edge of each sash 40 is provided with a groove 54 spaced inwardly from the face of the sash by the width of the web 13. The U-shaped portion 11 of the weather stripping enters the groove 54. The U-shaped portion 12 enters a groove 55 cut into the face of the blind stop 45 which contacts the face of the sash. As shown in Fig. 10 the pulley frame 53 is preferably set, transversely of the width of the side jamb, at such a position that its protruding hood portion is contacted by the adjacent edge of the flange 11c.

This helps to position the weather stripping. While the weather stripping may if desired be nailed or otherwise fixed to the side jamb or to the blind stop, it is not necessary that this be done. On the contrary, I find it preferable to leave the weather stripping unattached. Because it is in a sense floating, it is self-aligning with the groove in the sash. The weather stripping extends all of the way from the head jamb down to the sill. No matter at what elevation the sash may be, substantially one-half of the length of the weather stripping is engaged by the groove 54 in the sash, so that the sash tends to position it. To remove the weather stripping, the sash may be moved to its lowermost position, and its unfixed upper end of the strip may be pulled out and the entire strip drawn upwardly withdrawing it from its grooves in the sash and the blind stop. The flexibility of the weather stripping permits this. The fact that the side weather stripping is not fixed to the frame or sash greatly simplifies the operation of removing the sash where the outside stop would have to be removed.

The U-shaped portion 11 of the lateral weather stripping for the lower sash 48 is received in a similar groove 58 on the inside stop 44.

In the instance of the sash grooves 54 as well as in the instance of the stop grooves 55 and 56, the grooves are of slightly less width than the normal width of the U-shaped portion of the weather stripping which they receive. Consequently the weather stripping exerts a spreading action and results in a two-point seal at any transverse section of the groove. Because of this relation a slight transverse movement of the sash, while it might similarly transversely move a floating weather strip, does not substantially affect the seal of the weather stripping with the groove and the stop. The floating weather stripping and the compressed fit of the U-shaped portions of the weather stripping in the grooves make possible a relatively loose fit of the reciprocating sash between the stops without impairing the quality of the seal afforded by the weather stripping. Ample clearance for the sash may be provided to forestall its sticking without impairing the weather tightness of the window as effected by the weather stripping. The weather stripping also acts with a mild braking effect on the sash as it is reciprocated, thus avoiding the falling of the sash if the weights are not adequate. This braking effect is the result of the friction developed by the slight spreading action of the U-shaped portions 11 of the weather stripping which work in the grooves 54 of the sash.

In the upper edge of the upper sash a groove 57 similar to the grooves 54 is formed. As the upper sash is closed, the groove 57 receives the U-shaped portion 11 of the top weather strip, as shown at the top of Fig. 9. Here the U-shaped portion 12 of the weather stripping is received in a groove 58 in the top blind stop 45. The top weather stripping may be held in place by nails 59 driven through the web portion 13 into the head jamb 41. Otherwise there would be nothing to hold the weather stripping in position when the upper sash was down except the friction of the U-shaped portion which enters the groove 58. Nailing the top weather stripping to the head jamb or the top blind stop does not interfere with removal of the sash.

For sealing the bottom of the lower sash, the U-shaped portion 12 of the lower weather strip is received in a groove 60 formed jointly in the stool and sill. Here also the weather strip is preferably nailed to the frame. As the lower sash is closed the U-shaped portion 11 of the weather strip enters a groove 61 in the bottom of the sash which is similar to the side grooves 54. While the lower weather strip is not floating, the upper part of the U-shaped portion 11 is rounded so that it tends by a camming action to pull the lower end of the sash into proper position if the sash be loose in the frame. Failing this, the inherent flexibility of the weather stripping would permit the necessary slight deformation in the cross section of the weather stripping to insure its entering the groove and making a weather tight seal against the walls thereof. The same action is true of the top weather strip.

The shallow depression cut adjoining the groove, for the reception of the flange 12c of the strip, is somewhat deeper in the instance of the top and bottom of the double hung sash than in the instance of the casement sash. This is to eliminate danger of the flange 12c being caught by the corner of the double hung sash as it moves past the flange 12c. Also, as will be seen from a close

inspection of Fig. 1, the flange 12c is at a slightly acute angle to the leg 12b. This tends to draw the raw edge of the flange 12c further into its depression.

In the instance of the inter-sash seal—the seal between the top of the lower sash and the bottom of the upper sash—the relation of the weather stripping to the sash is somewhat different than in the other applications heretofore described. Referring to the metal section of Fig. 9, the top rail of the sash 48 has a down-facing shoulder 62 which, when the two sashes are closed, overlies and rests against an up-facing shoulder 63 on the bottom rail of the upper sash 49. A groove 64 is formed on the outer face of the upper rail of the sash 49 and below the shoulder 63. In this groove 64 is secured, as by nails, the U-shaped portion 11 of the inter-sash weather strip. The strip is thus carried by the sash 49 with its U-shaped portion 12 extending upwardly above the shoulder 63. The U-shaped portion 12 is received by a groove 65 formed in the shoulder 62 of the lower sash 48.

The slight obliquity between the surfaces which carry the weather strip and the direction of movement of the sash, in the instance of the bottom and the inter-sash sealing strips, is absorbed in the resilience of the material of the strip.

The weather strips for the sides of the lower sash and for the bottom of the lower sash are co-planar; therefore their corners may be mitered at the lower ends of the lateral strips. The same is true of the upper ends of the lateral strips for the upper sash 49 where they meet the top strip. These are the meeting corners of the weather strips which have to be sealed when the sashes are closed. Mitered corners can be made substantially weather tight. The ends of the inter-sash weather strip come against the inside face of the lateral parting stops 46.

As previously stated, my weather stripping does not interfere with the removal of the sash from a double hung window. To remove the sash, the retaining screws 66 for the inside stops 44 are removed and then the stops themselves are removed. By lifting the lower sash 48 a little, the sash together with its lateral weather strips may be pulled inwardly, that is, toward the room. Or, as previously described, the lateral strips may be withdrawn upwardly. Then the parting stops 46 may be removed, the lateral weather strips for the upper sash may be withdrawn as previously described and that sash removed inwardly. The bottom strip and the top strip are left undisturbed on the frame. The inter-sash strip is carried by the sash 49.

If the sash be fitted to the frame at the factory, the grooves may initially cut to the most advantageous depth. However if the sash are made slightly oversize to be fitted to the frame by the carpenter "on the job" the grooves 54, 57, and 61 may be made as much deeper as the sash is made oversize. An excessive depth to these grooves will not impair the functioning of my weather stripping.

While I have described these specific embodiments of my invention I contemplate that changes may be made therein and other applications made of my weather stripping as well as changes in my weather stripping, without departing from the scope or spirit of my invention.

In the claims, for lack of a better term, I have used fenestral in the broader sense of pertaining to doors and door frames as well as swinging or sliding windows and window frames.

I claim:

1. A weather stripping comprising a strip of sheet metal of a cross section arranged in a 5-shape comprising a first open U-shaped portion, a second open U-shaped portion of a size of the order of the first U-shaped portion, the second U-shaped portion being disposed with its bight facing the adjacent leg of the first U-shaped portion, one leg of the second U-shaped portion being extended as a web co-planar and connecting with the end of said adjacent leg of the first U-shaped portion, the web being of such length that the other leg of the second U-shaped portion terminates short of the said leg of the first U-shaped portion by a distance of the order of the lengths of the U-shaped portions.

2. A weather stripping formed of sheet metal and comprising in section a first open U-shaped portion whose breadth is in the order of its length, a second open U-shaped portion whose breadth is in the order of its length, the sizes of the two U-shaped portions being of the same order, the second U-shaped portion being open but disposed at right angles to the first U-shaped portion in a 5-shape with the bight of the second facing the adjacent leg of the first, the leg of the second toward the open end of the first being extended as a web and joining the outer end of the said adjacent leg of the first, the first U-shaped portion being adapted for reception in a groove in a fenestral member of wood spaced inwardly from a running corner, the length of the web extension being such that the other leg of the second U-shaped member terminates short of the said leg of the first U-shaped member by a distance sufficient to permit the corner stock of the member of substantial thickness and strength to be inserted within the distance.

3. The combination with a fenestral member having a first and a second face forming a running salient corner with a groove in the first face spaced away from the corner to leave corner stock of substantial thickness,—of a weather strip formed of sheet metal and comprising a first open U-shaped portion received within the groove with its bight facing outwardly, a second open U-shaped portion disposed at right angles to the first U-shaped portion with its bight facing the second face adjacent the corner, one leg of the second U-shaped portion projecting beyond the corner and over that portion of the first face between the corner and the groove and connecting with the end of the adjacent leg of the first U-shaped portion, the other leg of the second U-shaped portion terminating substantially at the second face.

4. The combination with a fenestral member having a first and a second face forming a running corner with a groove in the first face spaced away from the corner to leave corner stock of substantial thickness,—of a weather strip formed of sheet metal and comprising a first U-shaped portion received within the groove with its bight facing outwardly, a second U-shaped portion disposed at right angles to the first U-shaped portion with its bight facing the second face adjacent the corner, one leg of the second U-shaped portion projecting beyond the corner and over that portion of the first face between the corner and the groove and connecting with the end of the adjacent leg of the first U-shaped portion, the other leg of the second U-shaped portion terminating substantially at the second face, and carrying an offset terminal flange extending along the second face away from the corner, the sec-

ond U-shaped portion being constructed and arranged as a protruding bead for weather sealing reception in a groove of a second fenestral member moving relatively to the first member.

5. A weather stripping comprising a strip of sheet metal formed into a cross section of 5-shape comprising a first U-shaped portion, a second U-shaped portion disposed at right angles to the first portion and spaced therefrom with the bight of the second portion facing the adjacent leg of the first portion, a web portion interconnecting one leg of the second portion with the outer end of the said adjacent leg of the first portion, and the other leg of the second portion terminating a substantial distance from the said leg of the first portion in an offset flange extending away from the first mentioned leg of the second portion.

6. A weather strip formed of sheet metal and comprising in cross section a first U-shaped portion, a second U-shaped portion disposed at right angles to the first portion with its bight facing the adjacent leg of the first portion, the leg of the second portion nearest the open end of the first portion being extended and connected with the outer end of the said leg of the first portion, the other leg of each portion carrying at its outer end an offset terminal flange extending away from the first mentioned leg of the respective portions, the beforementioned parts being so constructed and arranged that the interconnected legs of the respective portions are mutually reinforced and stiffened and the other legs of the respective portions are reinforced and stiffened by their terminal flanges.

7. The combination with a fenestral closure hingedly mounted to swing in its frame and having an edge forming a running corner with its face, of weather stripping means for the closure for sealing it to its frame comprising a groove in the edge spaced inwardly from the corner to leave substantial stock between the groove and the corner and a sheet metal weather strip carried by the closure 5-shaped in cross section and comprising a U-shaped portion received and secured within the groove and a second U-shaped portion, having an extended leg, embracing the corner and disposed at right angles to the first portion with its bight facing the adjacent leg of the first portion, the extended leg joining the outer end of the said leg of the first portion and the other leg extending to the face inwardly of the corner and terminating a substantial distance short of the groove to permit the extension therebetween of substantial stock for supporting the corner, the second U-shaped portion being constructed and arranged as a protruding bead for weather sealing reception in a groove of the frame.

8. The combination with a fenestral closure hingedly mounted to swing in its frame and having a free edge forming a running corner with its face, of weather stripping means for the closure for sealing it to its frame comprising a groove in the edge spaced inwardly from the corner to leave substantial stock between the groove and the corner and a sheet metal weather strip carried by the closure and comprising in cross section a U-shaped portion received and secured within the groove and a second U-shaped portion protruding laterally from the face having an extended leg embracing the corner and disposed at right angles to the first portion with its bight facing the adjacent leg of the first portion, the extended leg joining the outer end of the said leg of the first portion and the other leg of the

second portion being disposed inwardly of the extended leg, the second U-shaped portion being constructed and arranged for weather sealing reception in a groove of the frame.

5. 9. The combination of a fenestral closure having an edge and a face forming a running corner, a fenestral frame for the closure having a jamb facing the edge and a stop facing the face adjacent the corner, and a hinge pivoting the door 10 to the jamb at the edge corner opposite from the said face,—weather stripping means for weather sealing the closure to the frame comprising a groove in the edge spaced inwardly from the corner to leave a substantial stock of the closure therebetween, a groove in the stop facing the face of the closure adjacent the corner, and a sheet metal weather strip comprising in cross section a first U-shaped portion facing the jamb and constructed and arranged to be received within 15 the groove in the edge as the closure closes to effect a weather sealing contact with the walls of the groove, a second U-shaped portion received within the stop groove and disposed with its bight facing the adjacent leg of the first portion, the second portion having an extending leg lying along the jamb and connected at its end to the said leg of the first portion, the other leg of the second portion terminating inwardly of the corner and at a substantial distance from the groove to 20 permit the extension therebetween of substantial stock of the closure for supporting the corner, the strip being secured and carried by the frame.

10. The combination of a fenestral closure having a facing and lateral edges at the opposite sides thereof, the edges forming with the face respective running lateral corners, a frame for the closure having opposite jambs facing the respective edges and stops facing the face adjacent the respective corners, a hinge pivoting the closure to the jamb adjacent one edge opposite said face,—of weather stripping means for sealing the closure to the frame comprising a groove in each edge spaced inwardly from the corner to leave substantial stock of the closure therebetween, a groove in each stop facing the face adjacent the corner and being disposed adjacent the jamb, and a pair of sheet metal weather strips, one at each edge, each strip comprising in section a first portion received within one of the edge grooves and a second portion which is U-shaped protruding beyond the face of the closure, received in the adjacent stop groove, the second portion being disposed facing the first portion, one leg of the second portion being extended beyond the corner across the edge and joined to the first portion and the other leg of the second portion extending toward the face at a distance from the edge, the strip at the hinge edge being carried by the frame and the strip at the other edge being carried by the closure.

60 11. The combination with a fenestral closure having a lateral running corner formed by an edge and a face, a frame therefor, and a hinge for pivoting the closure on the frame at a corner diagonally opposite the said corner, the frame comprising a jamb parallel with and facing the edge and a stop facing the face adjacent the edge,—of weather stripping means for sealing the closure to the frame comprising a groove in the edge a spaced distance inwardly from the corner leaving a substantial thickness of stock between the corner and the groove, a groove in the stop facing the corner, and a sheet metal weather strip comprising a portion secured in the groove and a second portion which is U-shaped protrud-

ing beyond the face at the corner with its bight facing toward the groove and having a leg extending to and joined with the first portion, the other leg of the U-shaped portion extending toward the face at a distance inwardly from the corner, the extended leg of the second portion normally lying along the edge, but, when the second portion enters the groove, being deflected away from the edge and toward the adjacent wall of the groove by camming contact of the other leg of the U-shaped portion with the other wall of the groove, whereby the protruding portion tends to clear the jamb as the closure opens, but the respective legs of the U-shaped portion seal against the respective walls of the groove in 15 the stop when the closure is closed.

5 12. In weather stripping the combination of a fenestral closure having a vertical and a horizontal edge forming together with a face a tri-planar corner, a groove formed in each edge 20 spaced inwardly from the face to leave a substantial thickness of stock between the groove and the face, and weather strips one in each groove, each strip comprising a U-shaped portion received and secured within one of the respective grooves and 25 a second and U-shaped portion protruding beyond the face at the edge and having an extended leg connecting with the first portion and a short leg extending toward the face at a distance inwardly from the edge, the strips being co-planar and 30 joined at the corner by a miter joint.

13. The combination of a window comprising a jamb and a pair of spaced stops having opposed faces which together with the jamb constitute a sashway, a sash slidably mounted with its edge 35 in the sashway and weather stripping means for sealing the sash to the sashway comprising a groove in the edge of the sash, a groove in the said face of one of the stops, and a sheet metal weather strip disposed in the sashway and comprising in cross section a first U-shaped portion received in the edge groove with its bight facing the jamb, a second U-shaped portion received in the face groove and disposed with its bight toward the first portion, one leg of the second portion being 40 extended along the jamb and connected with the adjacent leg of the first portion and the other leg of the second portion terminating a substantial distance from the groove to permit the extension of a substantial thickness of stock between 45 the second leg and the groove.

14. The combination of a window comprising a jamb and a pair of spaced stops having opposed faces which together with the jamb constitute a sashway, a sash slidably mounted with its edge 55 in the sashway and weather stripping means for sealing the sash to the sashway comprising a groove in the edge of the sash, a groove in the said face of one of the stops, and a sheet metal weather strip disposed in the sashway and comprising in cross section a first U-shaped portion received in the edge groove with its bight facing the jamb, a second U-shaped portion received in the face groove and disposed with its bight toward the first portion, one leg of the second portion being 60 extended along the jamb and connected with the first portion and the other leg of the second portion terminating a substantial distance from the groove to permit the extension of a substantial thickness of stock between the second leg and the groove, the strip being carried by the frame and free to float transversely to the sashway.

15. In a double hung window, the combination of a frame, a sash vertically slidably therein, a horizontal frame member which a horizontal edge 75

of the sash approaches when the sash is closed, and weather stripping means for sealing the sash edge to the frame member comprising a groove in the sash edge facing the frame member, a groove 5 in the frame member facing in a direction at a right angle to the edge groove and a weather strip comprising a first U-shaped portion protruding from the frame member and constructed and arranged to be received by the edge groove 10 in weather sealing contact therewith when the window is closed and a second U-shaped portion disposed within the frame groove and having an extended leg connected with the adjacent leg of the first portion, the strip being carried by the 15 frame.

16. In a window the combination of a jamb having a sashway forming face, a blind stop having a face forming an edge of the sashway, the stop and jamb having interconnecting tongue 20 and groove members with the tongue projecting in a direction transversely to the face of the jamb, the tongue and groove members being set away from the face a sufficient distance to permit a substantial thickness of stock between the tongue 25 and face for supporting the tongue, a sash having an edge reciprocable in the sashway, a groove in the edge of the sash, a groove in the face of the stop and a metal strip having a portion received in the edge groove and a portion received in the stop groove, the stop groove having one wall substantially coplanar with the face of the jamb.

17. The combination with a window having a frame, a pair of sash, and sash-ways in the frame in which the sash slide in parallelism, of inter- 30 sash weather sealing means between the juxtaposed rails of the respective sash when in closed position, comprising Z-shaped mating surfaces for the adjoining faces of the juxtaposed rails providing for each surface two parallel portions offset by a transverse portion, a groove in the 35 transverse portion of the mating surface of one rail face opening toward the transverse portion of the surface of the other rail face, a second groove in one of the parallel portions of the other rail face opening toward the mating parallel face of the first rail face and on that side of the trans- 40 verse portion toward which the first groove faces, and a length of weather stripping of 5-shaped cross section comprising two U-shaped portions, one of which is carried in the second mentioned 45 groove and the other of which is adapted to be received in the first groove when the sash are slid to closed position.

18. The combination of a window comprising a jamb and a pair of spaced stops having opposed faces which together with the jamb constitute a sashway, a sash slidably mounted with its edge in the sashway and weather stripping means for sealing the sash to the sashway comprising a groove in the edge of the sash, a groove in the said face of one of the stops, and a sheet metal weather strip disposed in the sashway and comprising in cross section a first U-shaped portion received 10 in the edge groove with its bight facing the jamb, a second U-shaped portion received in the face groove and disposed with its bight toward the first portion, one leg of the second portion being extended along the jamb and connected with the 15 first portion and the other leg of the second portion terminating a substantial distance from the groove to permit the extension of a substantial thickness of stock between the second leg and the groove, the strip being slidably received in 20 both grooves.

19. The combination of a window comprising a jamb and a pair of spaced stops, the jamb having an inner surface and the stops having opposed lateral surfaces, whereby the three surfaces define an inwardly opening sashway, a sash having an edge surface and adjoining parallel face surfaces for reception by the sashway, a groove in one of the sash surfaces, another groove in one of the sashway surfaces, and a 30 length of weather stripping of 5-shaped cross section comprising as a part of the 5-shape a U-portion received in one of the grooves and a second U-portion received in the other groove.

20. A combination with a fenestral frame of 35 a pair of fenestral closures therefor hinged at their opposite edges to the frame and having juxtaposed free edges, the juxtaposed free edges being contoured to mating Z-shaped cross section, providing a pair of parallel transverse surfaces offset by a longitudinal surface coplanar 40 with the closures, a groove in the transverse surface of one of the sash and a second groove in one of the parallel surfaces of the other sash on that side of the longitudinal surface toward which the 45 first groove faces, and a length of weather stripping of 5-shaped cross section comprising a first U-shaped portion which is carried within the second mentioned groove and a second U-shaped portion which is received by the first mentioned 50 groove when the sash are swung to closed position.

ANTON A. GUILLAUME.
